UNITED STATES PATENT OFFICE.

LESLIE P. MICK, OF CHICAGO, ILLINOIS.

DESICCATING-MACHINE.

1,118,304.

Specification of Letters Patent. Patented Nov. 24, 1914.

Application filed November 1, 1913. Serial No. 798,611.

To all whom it may concern:

Be it known that I, LESLIE P. MICK, a citizen of the United States, residing at Chicago, in the county of Cook and State of Illinois, have invented a certain new and useful Improvement in Desiccating-Machines, of which the following is a specification.

My invention relates to desiccating machines and applies more particularly to the desiccation of milk or other fluid food products.

The object of the invention primarily is to provide a continuously operating apparatus in which the entire process is automatic and manual handling of the product is eliminated.

Another object is to render it possible to accomplish desiccation in a single self-contained machine instead of in a building structure or a room or chamber constituting part of a stationary building.

As contributing to the general object of the invention, it is my purpose to provide a comparatively small and light machine capable of ready inspection both internally and externally; also to provide means whereby the desiccating product may be removed from the machine pneumatically, thereby rendering conditions sanitary both as regards the product and the attendant and reducing the amount of attention necessary.

I accomplish my objects by the mechanism illustrated in the accompanying drawings, in which—

Figure 1 is a longitudinal sectional elevation of the complete machine. The plane of section is indicated by the line 1—1, Fig. 2. Fig. 2 is an end-elevation of the machine looking toward the left in Fig. 1. Fig. 3 is a sectional elevation on the line 3—3 Fig. 1. Fig. 4 is a longitudinal section showing the construction at the ends of the machine, the plane of section being indicated by the line 4—4, Fig. 2.

Similar numerals refer to similar parts throughout the several views.

In the form selected to illustrate the invention there is a stationary frame work comprising two stationary parallel end frames 1, 2 mounted upon a base 3. These end frames may be secured in different ways but by preference they are held by four tie rods 4, supported in arms 5 inte-

gral with the frames and extending beyond the circumference of the screen which will presently be described.

For convenience a number of man holes 6, herein shown to be circular in form are 60 removably secured in the end frames. In each end frame there is a number, preferably four, of anti-friction rollers 7 for supporting the screen rings 8. The precise manner of mounting these rollers is immaterial but in the preferred form, they are supported upon studs 9, the inner ends of which are supported directly in the frame, the outer end being supported in a plate 10. Said plates are here shown to be circular in 70 form and fitting into the corresponding recesses in the outer faces of the end frame. As a result of this construction, the studs are rigidly supported at both ends and the rollers are entirely closed. 75

The gear rings, mentioned, support and may be regarded as forming a part of the revolving screen in which the desiccation takes place. The sides 11 of the screen consist preferably of copper cloth of a very 80 fine mesh, for example, 100 or finer. This cloth is supported upon a suitable frame work, which according to the present design consists of a number of longitudinal bars 12 bolted at the ends to the rings 8 and 85 braced by a number of rings or bands 13 which support the screen cloth.

Means are provided for rotating the screen slowly, the preferred means being spur teeth 14 formed upon the screen rings 90 and driven by a pinion 15 mounted upon a shaft 16. Said pinion is fastened to a bevel gear 17 which meshes with a bevel pinion 18 fastened to shaft 19 journaled in brackets 20 located upon the end frame at one end 95 of the machine. Shaft 19 may be driven in any suitable manner, for example, the band wheel 21, see Fig. 2.

At one end of the machine, which for convenience will be termed the front end, 100 are atomizers 22. These are preferably two in number located equi-distantly on opposite sides of the axis of rotation of the screen. The milk or other product to be desiccated is forced into said atomizers through pipes 105 23. The atomizers are preferably supported in the frame and are therefore stationary and may be of any suitable pattern, the essential characteristic being that they shall be capable of sub-dividing the milk into a 110

fine spray or mist. The atomizers should be capable of injecting the milk spray with considerable force toward the back frame plate of the machine where a duct 24 delivers a current of air into the machine as shown at the left end of Fig. 1. Preferably duct 24 has a rectangular delivery mouth, the greatest dimension whereof is horizontal as best shown in Fig. 3. This causes the air to be distributed laterally over a large area, the air entering the machine in a horizontal sheet, so to speak. While it is preferable that the atomizers and air duct should enter the screen at approximately the level of the axis of rotation, this is not essential and the elevation may be varied somewhat without departing from the spirit of the invention.

To facilitate inspection, it is well to provide an indicator lamp 26 in one or both of the end frames.

A vacuum conveyer is located at the bottom of the machine and comprises a number of vacuum heads 27 communicating with and supported upon the conveyer duct 28. The dead end of said duct is preferably supported in the front end frame 2 while the delivery end is supported in rear frame 1. The preferred cross section of the vacuum heads is shown at the bottom of Fig. 3 where it will be seen that the sole is approximately cylindrical but with a radius of curvature much smaller than the radius of the screen. The center of the sole closely approaches the inside surface of the screen with the result that when a vacuum is created in the duct 28, the fine particles of desiccated milk or other product will with certainty be sucked up into the vacuum head and conveyed from it through the duct 28 into any suitable receptacle provided for the purpose outside of the machine. On the far side of the vacuum heads (that is, the side last reached by any given point on the screen) it is desirable to place the confining apron 29 consisting preferably of felt or some other material practically impervious to air. This apron is flexible and drags upon the inner surface of the screen and serves the purpose of preventing the air from entering into the vacuum heads except from beneath or from the near side thereof. In the best form the vacuum head is made in a number of non-communicating sections or units bolted or otherwise secured together as suggested in Fig. 1. These sections are distributed along the conveyer duct 28 and in the preferred design said duct is larger in cross section at the delivery end than at the end farthest therefrom. In other words, the duct preferably increases in diameter toward the delivery end, the purpose being to keep the intensity of vacuum equalized in the different sections of the vacuum head.

In operation, the screen is first started and caused to revolve at a slow rate of speed, for instance, two revolutions a minute. The air blast is then turned on and air, preferably at a high temperature, for example, 300° Fahrenheit, is introduced into the machine through the duct 24. This is injected with considerable force and the air moves with considerable rapidity toward the atomizers. After the air blast is started, the attendant turns on the atomizers and causes them to introduce the milk or other product in the form of a spray or fog, directing it with considerable force toward the entering hot air blast. This causes the water content of the milk to become evaporated while the solid content is separated out in the form of a powder. The air and water vapor escape through the walls of the screen but the solid particles are prevented from passing out. Gravity causes the larger proportion of the desiccated product to fall directly to the bottom of the screen and to be conveyed immediately through the vacuum head to and through the duct 28. Such portion of the product as is lodged upon the inner surface of the screen is conveyed by the rotating screen to a point beneath the sole of the vacuum head whence it is sucked up through them and into, and through the conveyer duct. The apron 29 acts as a shield to prevent the air from entering except approximately diametrically through the mesh of the screen or at a point on the near side (the side first approached by the revolving screen). As a result of this arrangement of the parts the vacuum head not only serves as means for removing the desiccated product but acts as a cleaner to keep the ramifications of the screen constantly clear and open. In addition to this the apron, dragging (as it should) upon the inner surface of the screen, serves to loosen any particles which might by any chance be caught in the meshes of the screen; consequently when such loosened particles again come under the vacuum head, it will be extracted with the rest.

It will be understood that the temperature of the air entering through the blast pipe 24 may be varied and should at all times be so regulated as to prevent the milk from being raised to a temperature where a chemical change would occur. But on account of the fact that the screen is exposed to the atmosphere on all sides, it is constantly being cooled and, therefore, a higher temperature of air blast may be used with safety than if the desiccation occurred in a chamber with impervious walls. In other words, in my machine on account of the large surface exposed and the consequent rapid dissipation of heat, a higher temperature air blast may be safely employed than if desiccation took

place in a more or less completely closed chamber.

Having thus described my invention, what I claim as new and desire to secure by Letters Patent, is:

1. A desiccating machine comprising a substantially cylindrical dust collecting screen revolving about a substantially horizontal axis, a vacuum head located within said screen and having its receiving mouth close to the internal surface of the screen near the lowest point thereof, and a duct leading from said vacuum head and passing out through the end of said screen for removing the solid particles therefrom.

2. A desiccating machine comprising a revolving screen closed at the ends and revolving about a substantially horizontal axis, an atomizer for introducing fluid into said screen, and a stationary vacuum head within said screen, said vacuum head practically touching the inner surface of the screen for forcibly withdrawing particles lodged against it.

3. A desiccating machine comprising a revolving screen, an atomizer discharging thereinto, a multi-section vacuum head within said screen for withdrawing the desiccated material and a conveyer duct communicating with the sections of the vacuum head and leading to the exterior of the machine, different portions of said duct being of different diameter for rendering the suction within the various sections of the vacuum head uniform.

4. A desiccating machine comprising a revolving screen arranged approximately horizontal, stationary end frames for said screen, geared screen rings for rotating said screen, anti-friction rollers for supporting said ring upon said end frames, and an atomizer delivering through one of said end frames for introducing fluid into said screen.

5. A desiccating machine comprising a revolving screen, imperforate end frames, an atomizer supported in one of said end frames and discharging into said screen, an air duct supported in the other end frame for delivering air into said screen and means within said screen for automatically removing the contents thereof.

6. A desiccating machine comprising a revolving screen having a substantially horizontal axis and composed of foraminous material of fine mesh for retaining high comminuted particles of solid matter, stationary end frames for supporting said screen, an atomizer delivering through one of said end frames, an air blast delivering through the opposite end frame, and means for sucking the desiccated material from the floor of said screen.

In witness whereof, I have hereunto subscribed my name in the presence of two witnesses.

LESLIE P. MICK.
